UNITED STATES PATENT OFFICE.

GEORGE W. GRIMINGER, OF CUYAHOGA FALLS, OHIO, ASSIGNOR OF ONE-HALF TO
CHARLES ROY LOSE, OF CUYAHOGA FALLS, OHIO.

PLIERS.

1,189,561.

Specification of Letters Patent.

Patented July 4, 1916.

Application filed April 25, 1916. Serial No. 93,449.

To all whom it may concern:

Be it known that I, GEORGE W. GRIMINGER, a citizen of the United States, residing at Cuyahoga Falls, in the county of Summit 5 and State of Ohio, have invented new and useful Improvements in Pliers, of which the following is a specification.

This invention relates to improvements in pliers, and the object of the invention is to 10 provide pliers with mechanism for locking the jaws against being moved to their open position after engaging an article, and further provided with mechanism for releasing the locking mechanism to permit releasing the jaws from the object.

With the foregoing and other objects in view, the invention consists in the novel construction, combination, and arrangement 20 of parts constituting the invention, to be hereinafter specifically described and illustrated in the accompanying drawings which form a part hereof wherein is shown the preferred embodiment of the invention, but it is to be understood that changes, variations and modifications can be resorted to 25 which come within the scope of the matter hereinafter claimed.

In the drawings in which similar reference numerals indicate like parts in the different figures, Figure 1, is a view in side elevation of pliers embodying this invention; Fig. 2, is a plan view of the device shown in Fig. 1; Fig. 3, is a longitudinal, central sectional view of a portion of one 35 member of the device taken approximately on line 3 of Fig. 2, showing the locking mechanism in its inoperative position; and Fig. 4, is a view similar to Fig. 3 showing the device in its locked position.

The device embodies two coacting members 1 and 2 pivotally united by a pin 3. The member 2 comprises a jaw 4 at one end and a handle 5 at the opposite end. The member 1 comprises a jaw 6 coöperating 45 with jaw 4 and a handle at the opposite end denominated by the numeral 7. The general formation of the pliers forming the subjectmatter of this invention including the jaws and handles are of conventional type and a further description of their general shape is believed to be unnecessary.

In the handle 5 of the member 2 is an elongated recess 8 and the portions of the handle on one side of the recess provide a

wall 9 and on the opposite side a wall 10. Extending through both walls 9 and 10 are two slots 11 and 12, both of which extend longitudinally of the handle 5. In the floor of the recess 8 is a communicating recess 11 for a purpose to be later described and extending downwardly through the floor of the recess 8 is a slot 12. In one end wall of the recess 8 is a recess 13 constituting a seat for a purpose to be later described. Mounted to move shuttle-fashion in the recess 8 is a carrier 14, less in length than the recess 8 and of the proper size to fit therein. The vertical thickness of the carrier 14 is such that the upper face will be approximately flush with the upper face of the handle 5, and extending through the front end of the member 14 is a pin 15 the ends of which project into the slots 11 for guiding and holding member 14 from being unintentionally removed from the recess 8. The carrier 14 is provided with a longitudinally extending recess 16 across which extends a bar 17 formed integrally with the member 14 and in the upper face of this bar 17 is a recess 18 constituting a seat for a purpose to be later described. The rear face of the carrier 14 is provided with a recess 19 in alignment with recess 13 and in these two recesses is seated a spring 20. On the upper face of the carrier 14 is a stud 21 constituting a thumb grasp. Extending transversely of the carrier 14 near the rear end thereof is a pin 22 which projects 50 through the slots 12 and is provided at its ends with heads 23, the pin 22 in the slots 12 serving to prevent upward movement of the carrier 14. Extending between the side walls of the carrier 14 and across the recess 16 is a pin 24, pivotally mounted on which is a latch 25 the front under face of which is provided with a recess 26 constituting a seat for a coiled spring 27 the opposite end of which is seated in the recess 18, and the normal tendency of this spring 55 is to hold the forward end of the latch 25 in its upper position. The lower rear face of the latch 25 is provided with a down-turned finger 28 arranged in longitudinal alignment with the recess 11 and fashioned to engage therein for constituting a lock to prevent forward movement of the carrier 14 when the latch is in its operative position as shown in Fig. 3.

Pivottally mounted in a suitable slot in the handle 7 of the member 1, by means of a pin 29, is a curved arm 30 the forward face of which is provided with teeth 31. The arm 5 30 is adapted to project through the slot 12 and through the recess 16 in the carrier 14 and when moved to its forward position the teeth 31 engage the wall which forms the floor of the recess 8 for preventing separation 10 of the handles 5 and 7 and the jaws 4 and 6.

The operation of the device is as follows: The jaws 4 and 6 are separated sufficiently to 15 grasp an object or article by separating the handles 5 and 7. As the handles 5 and 7 are forced toward each other to clamp the jaws 4 and 6 on the object the operator, usually employing his thumb forces the carrier 14 forward by means of the stud 21, and he 20 may also press downwardly on the catch 25 which depresses the forward end thereof thereby raising the finger 28 out of the recess 11, as shown in Fig. 4, which causes the cross-bar 17 to oscillate the toothed arm 30 25 forwardly to bring the teeth 31 into engagement with wall of the handle 5 which forms the floor of the recess 8 as clearly shown in Fig. 4. When in this position the spring 20 holds the carrier in its forward or operative 30 position and the pressure which is usually applied on the handles 5 and 7 to insure a gripping engagement of the jaws 4 and 6 on the object is thereby rendered unnecessary. When it is desired to release the grip 35 of the jaws 4 and 6 on the object the operator shifts the carrier 14 by means of the head 23 of the pin 22 rearwardly, overcoming the force of the spring 20 and thereby shifts the carrier 14 rearwardly allowing the finger 28 to ride over the lower floor surface 40 of the recess and engage in the recess 11. The engagement of the finger 28 with the side wall of the recess 11 is sufficient to hold the carrier 14 from being forced forward by the 45 spring 20. As the carrier 14 is shifted rearwardly the forward portion 32 of the carrier 14 will engage the teeth 31 and oscillate the arm 30 rearwardly to withdraw the teeth 31 from their engagement with the member 5.

50 I claim—

1. Pliers comprising complementary members pivottally united, each of said members having a jaw at one end and a handle at the opposite end, the handle of one member 55 provided with an elongated recess and a slot communicating therewith, a toothed arm pivottally connected with the handle of the other member and extending through the said slot and recess, a shifttable carrier positioned in said recess, means for normally shifting said carrier in one direction for causing engagement of the teeth on said arm

with the handle provided with said carrier, and a catch on said carrier adapted to hold said carrier in its inoperative position. 65

2. Pliers comprising complementary, co-acting, pivottally connected members, one of which is provided with a slot, a toothed arm extending through said slot and pivottally connected with the other member and arranged to interengage with said first member for locking said members in a determinate position, and longitudinally shiftable means in said slot for shifting said arm into and out of operative relation with said first 75 member.

3. Pliers comprising complementary, co-acting, pivottally connected members, one of which is provided with a longitudinally extending recess and an intersecting slot, a carrier shiftably mounted in said recess and provided with a slot capable of registration with the first slot, an arm having a toothed edge extending through said slots and pivottally connected with the other member and 80 arranged to be moved into and out of operative engagement with said first member by said carrier.

4. Pliers comprising complementary, co-acting, pivottally connected members, one of which is provided with a longitudinally extending recess and an intersecting slot, a carrier shiftably mounted in said recess and provided with a slot capable of registration 90 with the slot in said first member, an arm having a toothed edge extending through said slots and pivottally connected with the other member and arranged to be moved into and out of operative engagement with said first member by said carrier, and a catch 100 on said carrier interengaging with the said first member for holding said carrier and arm in their inoperative positions.

5. Pliers comprising complementary, co-acting, pivottally connected members, one of which is provided with a longitudinally extending recess and an intersecting slot, the carrier shiftably mounted in said recess and provided with a slot capable of registration 105 with the slot in said first member, and a spring for forcing said carrier and arm toward their operative position, an arm having a toothed edge extending through said slots and pivottally connected with the other member and arranged to be moved into and 110 out of operative engagement with said first member by said carrier, and a catch on said carrier interengaging with the said first member for holding said carrier and arm in their inoperative positions. 115

In testimony whereof I have hereunto set my hand.

GEORGE W. GRIMINGER.
